CONTROL SYSTEM FOR ELECTRIC LOCOMOTIVES

Walter Giger, Zurich, Switzerland, assignor to
Aktiengesellschaft Brown, Boveri & Cie.,
Baden, Switzerland

**Application March 23, 1945, Serial No. 584,378
In Switzerland March 3, 1944**

7 Claims. (Cl. 121—41)

1

Control systems for electric locomotives are known where by moving a hand controller drum on the operating platform the main controller which regulates in steps is actuated by a double-acting compressed air motor and the positions of the main controller are clearly determined by the engagement of a pawl. The same pawl can also act as a control element for the valves of the compressed air motor and can also be controlled by an electromagnet or compressed air. In order to avoid impacts the ratchet wheel with which the pawl engages is connected by means of a spring coupling with the shaft of the main controller. This known arrangement can also be used for multiple-way control systems.

Systems operated by compressed air possess certain disadvantages, however, which prevent their universal application. Since the compressed air motor is lubricated with oil or grease its operation depends very much on the ambient temperature and in cold weather the resistance which the motor has to overcome is many times greater than that occurring during warm weather. In cold weather the required air pressure is therefore considerably greater and the motor operates jerkily, so that the pawl and ratchet teeth are subjected to sudden high stresses which easily result in tooth fractures.

With control systems which operate with pressure oil these disadvantages do not occur. The pressure oil systems used up to the present are, however, very complicated and difficult to supervise and employ at least three valves; furthermore due to the differential pistons incorporated in the system the switching times vary according to the position, the recall motions are not uniform and the operation of the contacts is sluggish, so that the accuracy of the control system is detrimentally affected and the wear on the contacts is excessive.

According to the present invention all the aforementioned disadvantages are avoided. This is achieved by the fact that the smaller cylinder of the differential servomotor which is operated by pressure oil is maintained continuously under oil pressure, and the main switch shaft which is actuated by the servomotor is provided with a single-acting ratchet disc for the individual switch positions, the pawl associated with the ratchet when engaging this latter at the same time opening the pressure oil outlet below the larger piston of the differential motor, whereby the smaller piston of the differential motor presses the tooth of the ratchet disc corresponding to the switch position in question against the pawl.

2

A constructional example of the invention is illustrated in diagrammatic form in the accompanying drawing which shows an electro-magnetically operated pressure oil control system for a thermal-electric locomotive.

By rotating the main control shaft 1 the fuel supply to the thermal prime mover which can be either a turbine or an internal combustion engine is regulated or its speed governor influenced, 10 and if desired the generator and when necessary the traction motors of the locomotive are also controlled simultaneously. For transmitting control orders, there is provided a controller drum 2 rotatable by a manually operable crank 2a. 15 Drum 2 contains a stepped contact plate 2b, each step in the plate 2b corresponding to a separate switching position, these being designated on the drawing by the vertical dash-dot lines I-V. Associated with the rotatable plate 2b are stationary brushes 2c, there being a brush for each of the several steps in the plate 2b, and also a brush for connecting the positive side (+) of a power supply to plate 2b. 20

A stationary switch movement indicating controller drum 3 having arcuate contact rows *c*, *d*, *e* and *f*, interconnected as shown, is supported coaxially with the shaft 1. A rocker arm 27 is secured to and rotates with shaft 1, arm 27 bearing a plurality of insulated brushes 28 which make contact with the several contact segments on rows *c-f* as the arm 27 rotates. The several switch positions of rocker arm 27 relative to drum 3 are indicated by the horizontal dash-dot lines labeled 0-V and these correspond to the various switching positions of the manually rotated crank 2a. The several brushes 2c of controller 2 are connected, in order, to successive contact segments of contact row *c* by conductors *I'-V'*. As the drum 2 is rotated step by step, a circuit is completed from the positive side of the power supply through contact plate 2b through each of the brushes 2c, in order, and from these brushes through conductors *I'-V'*, and contact rows *c*, *d*, *e* and *f* to the coil of an electromagnetically operated valve 4 which controls a hydraulic motor 5. Hydraulic motor 5 is a differential motor with a large cylinder 6 and a small cylinder 7 the pistons of which by means of the toothed rods 8 and 9 act in opposite directions on the common toothed wheel 10 which drives the main control shaft 1 in the switching up (*a*) or down (*b*) direction. In order to ensure that the switch positions are exactly adhered to a ratchet wheel 11 operating in one direction only is provided on shaft 1, this wheel 11 being engaged by a pawl 12. This pawl 12 is brought into engagement with

ratchet wheel 11 by electromagnetic means or by hydraulic cylinder 14 which is controlled by electro-magnetic valve 13 and is provided with a counter-spring 15, whereby under the action of spring 17 and only during the last part of its stroke auxiliary contact 16 is opened or closed. Valve 13 which controls cylinder 14 is actuated by electro-magnet 18, whilst valve 4 for controlling differential motor 5 is actuated by two electro-magnetic coils, a main coil 19 and an auxiliary coil 20, and is provided with a counter-spring 21 and a self-holding contact 22 for auxiliary coil 20; in the circuit of coil 20 lies auxiliary contact 16. The current supply which is not shown in the drawing is connected to the system at + and -. The direction of flow of the pressure oil is indicated by the arrows shown in the figure. A low pressure relief valve 23 and two throttle valves 24, 25 are located in the pipes between valve 4 and hydraulic motor 5. The main control and regulating apparatus is coupled to shaft 1 at 26.

The method of operating the control system, which in the drawing is shown in the zero position, is as follows. If controller drum 2, which has five switch positions I-V, is for instance moved from position 0 to position I, then the circuit to the excitation coil 19 of valve 4 is closed over both outer contact brushes of controller 3. The piston of valve 4 is raised against the pressure exerted by spring 21 and thus allows pressure oil to flow to cylinder 6 of motor 5 whilst at the same time closing the oil outlet; valve 25 enables the switching-in speed to be regulated. Due to the excess power of the large piston 6 control shaft 1 is rotated in the switching-up direction indicated by the arrow a. When drum 2 is moved into position I and closes the circuit of coil 19 associated with valve 4, the circuit of coil 18 associated with valve 13 is also closed over brushes d and e of controller 3, and therefore the oil supply to valve 13 is shut off and its outlet opened, so that spring 15 in cylinder 14 presses pawl 12 against ratchet wheel 11 which rotates in a clockwise direction, whereby auxiliary contact 16 still remains closed due to spring 17. Contact 16 is only opened when pawl 12 slips into notch I in ratchet 11. In the meantime brush c has moved away from the top-most contact segment of contact row c of controller 3 and has interrupted the circuit of the main energizing coil 19 for valve 4, so that this latter is then only held by auxiliary coil 20 in conjunction with auxiliary contact 22. As soon as pawl 12 slips into a notch in ratchet wheel 11, the opening of auxiliary contact 16, however, also interrupts the circuit of coil 20 and valve 4 is then forced by spring 21 into the discharge position shown in the figure. The piston of the smaller cylinder 7 is subjected to a continuous oil pressure and causes tooth I of ratchet wheel 11 to be pressed sharply against pawl 12 so that this switch position is adhered to with great accuracy and as long as no further order is given by controller drum 2. As a result of the interruption of the contact row d of controller 3 the current in coil 18 is interrupted for a short time when between two switch positions and valve 13 is moved into the position shown so that cylinder 14 is supplied with pressure oil, pawl 12 is disengaged from ratchet wheel 11 and auxiliary contact 16 closed.

When moving up to higher switching positions the operation is performed in an analogous manner and independently of the fact whether the

drum 2 is moved in steps or if several or all switch positions are passed over at once.

The switching down operation occurs as follows. The control system is for instance in position V and has to be moved into position IV. In position V conductor V' between drum 2 and drum 3 is under voltage, coil 18 excited, cylinder 14 without pressure and pawl 12 in engagement with tooth V on ratchet wheel 11, so that shaft 1 cannot rotate in the direction indicated by arrow b. When drum 2 is moved back into position IV conductor V' and coil 18 are no longer under voltage. Cylinder 14 thus receives pressure oil and disengages pawl 12 from the tooth on ratchet wheel 11, so that the piston of the smaller cylinder 7 can turn shaft 1 backwards. Wheel 10 by means of toothed rod 8 thus also causes the pistons of the larger cylinder 6 to be pressed downwards. Since the main coil 19 of valve 4 is not excited the oil outlet from cylinder 6 over the switching-out speed regulating valve 24 and minimum pressure valve 23 is open. Valve 23 is adjusted to a pressure slightly above atmospheric so that cylinder 6 and the pipes between it and valve 4 are not completely emptied, even when the control system is out of operation.

After the switching-down operation has been initiated the brush associated with contact row d of controller 3 moves away from the last segment on contact row d which is without voltage and touches the next above contact segment of row d. This latter is, however, still connected with conductor IV' which is under voltage, so that coil 18 is excited again and pawl 12 pressed against ratchet wheel 11. As soon as position IV is reached, shaft 1 is blocked by pawl 12 which engages with notch IV on ratchet wheel 11, and since piston 7 exerts a constant torque on wheel 11 position IV is maintained until the next switching order is given.

If the control current fails, piston 14 remains constantly under pressure, so that pawl 12 remains disengaged and shaft 1 is returned to zero position by piston 7.

The most important advantage of the system described is that due to the constant pressure which prevails in cylinder 7 any desired switch position of shaft 1 can be adjusted for and adhered to with great accuracy. This is of particular importance as regards the control of speed governors for thermal prime movers. With this arrangement the ambient temperature and therefore the viscosity of the pressure fluid has no effect on the accuracy of the control system. Even poor joints in the pressure oil system or slight leakages past the pistons and glands do not affect the operation. The control cannot overrun the position for which it is adjusted or stop before it has reached the desired position. With a maximum simplicity of apparatus optimum safety of operation of the vehicle is thus obtained. The described system is quite suitable as a multiple-way control for the fine adjustment of the individual drives of several traction vehicles which are coupled together.

I claim:

1. In a hydraulic pressure operated switching control system, a manually operable controller having a plurality of operating positions, a rotatable shaft, a control device adapted to be rotated by said shaft, said control device having a plurality of operating positions each corresponding to an operating position on said controller, a ratchet wheel mounted on said shaft, said wheel 75 having a plurality of notches therein each cor-

responding to an operating position of said control device, a pawl cooperative with said notches, a hydraulic differential servo motor, said motor including pistons of different areas arranged to apply torque in opposite directions to said shaft, a source of hydraulic pressure, a conduit between said pressure source and the smaller of said pistons to maintain the latter under constant pressure, a second conduit between said pressure source and the larger piston, a valve in said second conduit, control means for said valve responsive to operation of said controller, control means for said pawl responsive to controller operation, said valve and pawl control means having an inter-relation such that when the pawl is engaged in a notch of the ratchet wheel, pressure is removed from the larger servo motor piston whereby the torque exerted by the smaller piston on said shaft causes the edge of said notch to be pressed against said pawl.

2. A control system as defined in claim 1 characterized by the feature that said pawl control means comprises an electrically controlled auxiliary hydraulic servo motor the piston of which actuates said pawl.

3. A control system as defined in claim 1 wherein said valve control means comprises an electro responsive device connected through a circuit which includes contacts actuated by operation of said pawl.

4. A control system as defined in claim 1 wherein said valve control means comprises an electro responsive device having a main coil and an auxiliary holding coil, the circuit to said holding coil including contacts actuated by operation of said pawl.

5. A control system as defined in claim 1 and

further including a regulating valve in said second conduit for determining the switching-in speed of said control device between operating positions.

5. 6. A control system as defined in claim 1 and further including a by-pass conduit from said second conduit through said valve to the low pressure side of said source, said by-pass conduit including a regulating valve which determines the 10 switching-out speed of said control device.

7. A control system as defined in claim 1 characterized by the feature that said valve control and pawl control means comprise electrically operated devices energized over circuit means controlled by said controller, and further including an auxiliary controller actuated by said shaft, said auxiliary controller including contacts connected in said circuit means.
